Primary Examiner — Clare E Heflin*(74) Attorney, Agent, or Firm* — Michael Best & Friedrich, LLP(57) **CLAIM**

I claim the ornamental design for a lighting fixture, as shown and described.

DESCRIPTION

FIG. 1 is a perspective view of a lighting fixture showing the new design;

FIG. 2 is a first side elevation view of the lighting fixture shown in FIG. 1.

FIG. 3 is a second side elevation view of the lighting fixture shown in FIG. 1.

FIG. 4 is a third side elevation view of the lighting fixture shown in FIG. 1.

FIG. 5 is a fourth side elevation view of the lighting fixture shown in FIG. 1.

FIG. 6 is a top view of the lighting fixture shown in FIG. 1; and,

FIG. 7 is a bottom view of the lighting fixture shown in FIG. 1.

The elements shown in broken lines are included for the purpose of illustrating portions of the lighting fixture that form no part of the claimed design.

1 Claim, 7 Drawing Sheets(56)
